[57] CLAIM

The ornamental design for a rail member for use in a carpet tufting device, substantially as shown.

DESCRIPTION

FIG. 1 is a side elevational view of a rail member for use in a carpet tufting device showing my new design;
 FIG. 2 is a bottom plan view thereof;
 FIG. 3 is an elevational view of the side of the member opposite that shown in FIG. 1;
 FIG. 4 is a top plan view thereof;
 FIG. 5 is an elevational view drawn from the left of FIG. 1;
 FIG. 6 is an elevational view of the end of the member opposite that shown in FIG. 5; and
 FIG. 7 is a perspective view of the end of the member shown in FIG. 5, the top and the side of the member shown in FIG. 1.
